UNITED STATES PATENT OFFICE.

MICHAEL I. PUPIN, OF NORFOLK, CONNECTICUT.

SOUND-GENERATOR.

1,899,877.

Specification of Letters Patent. Patented Dec. 13, 1921.

Application filed February 4, 1918. Serial No. 215,291.

To all whom it may concern:

Be it known that I, MICHAEL I. PUPIN, a citizen of the United States, residing at Norfolk, in the county of Litchfield, State of Connecticut, have invented certain new and useful Improvements in Sound-Generators; and I do hereby declare the following to be a full, clear, and exact description of the invention, such as will enable others skilled 10 in the art to which it appertains to make and use the same.

This invention provides a new form of oscillator for generating compressional waves, the object being to produce a rugged durable device of such character as to afford a large radiating surface as well as a large surface for the action of the impressed moving force, to permit the generation of sound waves of large energy at all frequencies. For this purpose I employ as the oscillating sound producing source an electrical condenser consisting of a cylindrical core constituting one element of the condenser, and a surrounding cylindrical shell, 25 separated by a dielectric from the cylindrical core, and constituting the other element of the condenser. When variations of electrical potential are applied to such a condenser, the cylindrical shell will be set into 30 vibration at a frequency corresponding to the frequency of the electrical variations, and will produce sound waves of corresponding frequency. In this way large amounts of electrical energy may be transformed 35 efficiently into compressional waves of any desired frequency. It will be noted that the apparatus has the advantage that the production of notes of high pitch does not involve any reduction of the radiating power 40 of the apparatus, as is the case in sound producers such as piano strings and the like.

In practice it is advisable to make use of electrical resonance to apply the electrical energy to the actuation of the oscillator in 45 the form of potential variations of great amplitude. For the purpose of further increasing the efficiency of transformation of the electrical energy into mechanical energy, it is desirable, in some cases, so to choose or 50 design the cylindrical shell that it has a natural period of mechanical vibration of the frequency of the sound waves to be produced. If electrical resonance is used in connection with a cylinder so chosen or designed, the resonant circuit will have the 55 same frequency, as will be understood.

A more particular understanding of the nature of the invention may be had from the following description of the preferred form of oscillator, together with means for transforming electrical energy into mechanical energy to actuate the oscillator. 60

In these drawings, Figure 1 is a cross-section of the oscillator used for sending purposes; Fig. 4 represents, somewhat diagrammatically, the position of the oscillator within a cylindrical parabolic mirror, the focal line of which is the axis of the oscillator, and Figs. 2 and 3 are diagrams representing the connections for applying electrical energy in two ways to the actuations 65 of the oscillator.

Fig. 1 illustrates an oscillator which I have constructed as an embodiment of my invention, and in describing it I shall refer 70 to the dimensions which have actually been employed. This particularity of description is for the purpose of enabling those skilled in the art, by the consideration of one particular form in which the invention has 75 been embodied, to understand the nature and principles of the invention, and it is not to be taken as limiting in any way the scope of the invention as defined in the accompanying claims. 80

In this device, 2 is a steel tube about .15 centimeters thick and having an internal diameter of 2 centimeters. 3 is a steel cylinder 1.975 centimeters in diameter and concentrically mounted within tube 2 so that the 85 cylindrical air space between them is .0125 centimeters thick. The cylinder 3 is held in position, and is insulated from tube 2, by the insulating plugs 4. In order to increase largely the difference of electrical potential 90 which may be maintained between the cylinder and shell I fill the space between them with compressed air. In this way, provided the insulating plugs 4 are suitably constructed to limit the electrical leakage from the 95 cylinder to the shell, as indicated, the electrical potential gradients can easily be made large, about 5×10^5 volts per centimeter, that is, an electrical potential may be maintained between the cylinder and shell of about 100 12,500 volts. It will be observed that the device constitutes a cylindrical electrical condenser. Insulated steel caps 5 and 6 serve to strengthen the structure so that 105 it will withstand high air compressions in the air space. When an alternating difference of electrical potential equal to $E \cos pt$ 110

volts is impressed between shell 2 and cylinder 3 the mechanical force F acting between them will have the following value in dynes per square centimeter:

$$5 \quad F = \frac{1}{8\pi} \left(\frac{E}{h} \right)^2 \frac{1}{9 \times 10^4} \cos^2 pt$$

where h is the thickness of the air shell which, as indicated above, is .025 centimeters.

10 This expression for F may also be written:

$$F = \frac{1}{16\pi \times 9 \times 10^4} \left(\frac{E^2}{h^2} \right) (\cos 2 pt + 1)$$

15 That is to say, the mechanical force acting between the cylinder and shell is equal to a constant force plus an alternating force of double the frequency of the impressed electrical difference of potential; that is, the 20 alternating mechanical force rises from zero to a maximum and falls again to zero for each half wave of the alternating electromotive force.

25 If $\frac{E}{h} = 5 \times 10^5$ volts then the amplitude of the alternating part of the mechanical force F will be

$$30 \quad \frac{25 \times 10^{10}}{16\pi \times 9 \times 10^4} \text{ dynes} = 55 \text{ grams, approximately.}$$

The alternating mechanical force acting upon the whole surface of a tube 30 centimeters long will be 10,365 grams.

35 In consequence of the action of this alternating force the steel shell will vibrate mechanically with the frequency speed 2 p. A similar result can be obtained by charging the oscillator to a constant electromotive 40 force of $\frac{E}{2}$ volts and then superposing upon it an alternating electromotive force equal to $\frac{E}{2} \cos 2 pt$.

45 The amplitude of these vibrations may be increased by causing the frequency of the force and the natural frequency of mechanical vibration of the tube to approach each 50 other and will be a maximum when resonance is reached. Since the amount of energy in the form of sound waves radiated from the tube is proportional to the square of the amplitude of vibration it is clear that 55 by resonance the sound energy which is emitted by radiation in the surrounding medium is increased.

A convenient method of actuating electrically the cylindrical oscillator of the character described is represented in two forms in Figs. 2 and 3. In Fig. 2 the core 3 and the shell 2 of the cylindrical oscillator are connected electrically by a circuit including inductance 11 and a secondary 12 of a transformer whose primary 13 receives an im-

70 pressed high frequency electromotive force from a suitable source, which may be, for instance, a vacuum tube oscillator of the well known form capable of delivering a large electrical output, say several hundred watts. The inductance 11 is variable so that the circuit may be tuned to increase the difference of electrical potential in the oscillator to any desirable value by electrical resonance.

75 The arrangement of Fig. 3 differs from that of Fig. 2 in that an auxiliary condenser 14 is connected in parallel with the oscillator and the two are kept charged by a direct current source 15 to a suitable difference of 80 potential, preferably equal to the amplitude of the alternating voltage and adjustable by means of the adjustable resistance 16. In this manner the difference of alternating potential to be supplied by the alternating 85 source through the transformer 12, 13, can be reduced to half of the value necessary in the arrangement of Fig. 2, but its frequency must be doubled. Under certain conditions the arrangement of Fig. 3 would offer substantial advantages.

80 In a steel shell of the character and dimensions above described the natural frequency of mechanical vibrations is given by the formula, taken from mathematical treatises on sound:

$$T = \frac{v}{2\pi r}$$

90 where T is the natural period of vibration, v is the velocity of propagation of sound in the steel of which the tube is made and r is the radius of the tube.

95 It is obvious from this formula that the circumference of the tube is equal to one 100 wave length of the natural vibration of the tube. For example, if v is equal to the usual value for tool steel, that is 5×10^5 c.m. per sec. then in my case $2r$ being equal to 2 centimeters the natural frequency of vibration will be approximately 8×10^4 pps.

105 This value of the natural frequency will be diminished by the resistance reaction of the surrounding medium. If the surrounding medium is air, the diminution will be inappreciable. If it is water, the diminution is considerably increased, but it can be kept within reasonable limits by increasing the thickness of the shell. Thus, when the thickness of the shell is .15 centimeters the reduction in the frequency given above will be 115 less than 1 per cent.

110 When the steel shell is vibrating in water under the action of a given force, the amplitude of vibration can be shown to be, within 125 wide limits, independent of the thickness when resonance is established. The thickness of the steel shell, on the other hand, should be as large as practicable, because the greater its thickness the greater can be the 130

pressure in the air film between the shell and the cylinder of the oscillator. Since the permissible value of this pressure is proportional to the thickness of the shell and 5 the permissible potential gradient between shell 2 and cylinder 3 is proportional to the air pressure, it follows that a shell n times as thick will permit a potential gradient n times as large which gives a force n^2 10 times as large. This again will produce an elastic displacement n^2 times as large and therefore a radiation n^4 times as large because the radiation is proportional to the square of the amplitude of vibrations.

15 When the oscillator is under water the damping is very considerable and no very sharp resonance exists, so that an oscillator of natural frequency equal to 8×10^4 pps can be operated by a force of frequency 10^5 20 pps without appreciable loss in radiation. This small loss will be more than compensated by the advantages gained from the higher frequency.

Another advantage which the steel tube 25 offers, particularly when its frequency is very high, say from 5×10^4 to 15×10^4 pps is that the cylindrical sound waves which it produces in the surrounding medium can be easily transformed into plane waves which 30 will be confined to a small space and form a parallel beam of sound waves. This is done by placing the tube oscillator with its axis on the focal line of a cylindrical parabolic mirror, as illustrated in Fig. 4. In 35 this figure 17 is a cylindrical parabolic mirror the focal axis of which coincides with the axis of the cylindrical oscillator 2, 3. According to well known rules the sound waves radiated from the oscillator will be reflected 40 by the cylindrical parabolic mirror to form a plane wave or beam of compressional waves sound confined to the prism parallel to the axis of the mirror and the cross-section of which is equal to the opening of the 45 parabolic mirror, provided the wave length is sufficiently small in comparison with the linear dimensions of the opening of the mirror. This condition is easily fulfilled by frequencies of 8×10^4 pps or higher 50 frequencies. In this manner a parallel beam of compressional waves sound is formed the direction of which can easily be changed by changing the position of the mirror or otherwise, just as in the ordinary searchlight 55 operations.

It can be shown theoretically and proved experimentally that the rate of radiation from an oscillator excited in the manner indicated will be about one watt when it is 60 placed in water. This is due to the fact that the elastic displacements are excessively small, somewhat less than 10^{-5} centimeters. Without resonance they would be considerably smaller.

65 In a companion application, Serial No.

215,292, filed February 4, 1918, I have described an apparatus for receiving and transforming into electrical energy the energy of the sound waves produced by an oscillator of the character above described, and I have 70 also there indicated how the compressional waves thus produced and received may be separated from, and rendered audible, without interference due to the ordinary sound waves and mechanical disturbances which 75 may be expected to exist under normal conditions in the sea.

It will be observed that the specific device above described is particularly adapted to the production of compressional waves of 80 a frequency far above audibility for use in a system of signaling involving a directed train of compressional waves together with a suitable receiver capable of receiving and rendering audible such waves, and that the 85 principles of electrical and mechanical resonance are made use of in connection with that device. It will, however, be understood that the invention is applicable, and of great value, in connection with the production of 90 audible and musical sounds and that the oscillator may be made of any suitable stiff material and may or may not be resonant to a particular frequency of audible sounds. Furthermore, by controlling the electrical 95 variation telephonically or otherwise in accordance with speech or musical sounds, the device, or a series of them, may be used as an effective producer or reproducer of such sounds.

I claim :

1. A generator of compressional waves comprising a stiff cylindrical body constituting one element of an electrical condenser, a second condenser element associated 105 therewith, a dielectric interposed between said elements for preventing a conductive flow of current therebetween, and means for imparting to the condenser varying electro-motive forces of a frequency corresponding 110 to the frequency of the compressional waves to be produced.

2. A generator of compressional waves comprising a stiff cylindrical body constituting one element of an electrical condenser, a second condenser element associated therewith, a dielectric interposed between said elements for preventing a conductive flow of current therebetween, and means for imparting to the condenser varying electro-motive forces of a frequency corresponding 115 to the frequency of the sounds to be produced, said means including a source of electrical energy, and an electrical oscillatory circuit connected to the said source and the 120 two condenser elements having a natural frequency substantially the same as the frequency of the compressional waves to be produced.

3. A generator of compressional waves 130

- comprising an electrical condenser having a cylindrical core and a cylindrical shell surrounding the core, a dielectric interposed between the shell and the core for preventing a conductive flow of current therebetween, and means for imparting to the condenser varying electromotive forces of a frequency corresponding to the frequency of the compressional waves to be produced.
10. 4. A generator of compressional waves comprising a stiff cylindrical body constituting one element of an electrical condenser, a second condenser element electrostatically associated therewith, a dielectric interposed between said elements for preventing a conductive flow of current therebetween, and means for imparting to the condenser varying electromotive forces of a frequency substantially corresponding to the natural period of mechanical vibration of the said body, whereby the electrical energy causes the body to oscillate resonantly.
5. A generator of compressional waves comprising a stiff columnar body constituting one element of an electrical condenser, a second condenser element electrostatically associated therewith and a dielectric interposed between said elements for preventing a conductive flow of electric current between said elements when an electromotive force is applied to the condenser.
6. A generator of compressional waves comprising a stiff columnar body constituting one element of an electrical condenser, a second condenser element electrostatically associated therewith, a dielectric interposed between said elements for preventing a conductive flow of current therebetween, and means for imparting to the condenser varying electromotive forces of a frequency substantially corresponding to the natural period of mechanical oscillation of the said body.
7. A generator of compressional waves comprising a stiff columnar body constituting one element of an electrical condenser, a second condenser element electrostatically associated therewith, a dielectric interposed between said elements for preventing a conductive flow of current therebetween, and means for imparting to the condenser varying electromotive forces having a frequency corresponding to the frequency of the compressional waves to be produced.
8. A generator of compressional waves comprising an electrical condenser having a columnar core and a concentric columnar shell of like configuration surrounding the core and separated therefrom by a dielectric of uniform thickness throughout for preventing a conductive flow of electric current therebetween, and means for imparting to the condenser varying electromotive forces of a frequency corresponding to the frequency of the compressional waves to be produced.
9. A generator of compressional waves comprising an electrical condenser having a cylindrical core and a concentric cylindrical shell surrounding the core, a dielectric interposed between the shell and the core for preventing a conductive flow of electric current therebetween, and means for imparting to the condenser varying electromotive forces of a frequency corresponding to the frequency of the compressional waves to be produced.
10. A sound generator consisting of a cylindrical electrical condenser, one element of which is a stiff body and in which the dielectric separating the two condenser elements is compressed gas, and means for imparting to the condenser potential variations of a frequency corresponding to the frequency of the sounds to be produced.
11. A sound generator consisting of a stiff cylindrical body constituting one element of an electrical condenser, a second condenser element electrostatically associated therewith, and means for imparting to the condenser varying electromotive forces of a frequency substantially corresponding to the natural period of mechanical oscillation of the said body, said means including a source of electrical energy and a resonant electrical circuit connected to the said source and to the two condenser elements and having a natural frequency substantially equal to the said frequency of mechanical vibration of the oscillator body.

In testimony whereof I affix my signature.
M. I. PUPIN.
